UNITED STATES PATENT OFFICE.

WILLIAM BERGERSON, OF BROOKLYN, NEW YORK.

SWIMMING AND BATHING APPLIANCE.

Application filed September 18, 1923. Serial No. 662,442.

To all whom it may concern:

Be it known that I, WILLIAM BERGERSON, subject to King Haakon VII of Norway, residing at Brooklyn, in the county of Kings and State of New York, have invented certain new and useful Improvements in Swimming and Bathing Appliances, of which the following is a specification.

This invention relates to an improved form of swimming and bathing appliance, and has particular reference to an improved form of sock adapted to be worn so as to enable a person to swim fastly and easily and to walk almost upright in the water with very little effort exerted solely for keeping a balance.

The primary object of the present invention is to provide a device of the above kind which embraces the desired qualities of simplicity, durability, and efficiency in operation, the device being particularly serviceable for use in connection with "water wings" or other similar appliances for assisting a swimmer to travel in the water or for assisting persons in learning to swim.

Other objects will appear as the nature of the invention is better understood, and the same consists in the novel form, combination, and arrangement of parts herein-30 after more fully described, shown in the accompanying drawings and claimed.

In the drawing, the view is a perspective view showing the device applied upon the leg and foot of the user, the device being shown in its operative position when the user is taking an impulsive stroke.

Referring more in detail to the drawing, the invention embodies a sock 5 adapted to be worn in a manner similar to ordinary articles of apparel known by that name and either constructed with a broad band as at 6 adapted to lie under the instep or to provide an entire covering for the foot as found most desirable. The sock is held against rolling 40 down by the provision of an elastic band 7 around the upper part thereof which functions to hold the sock snugly against the leg of the wearer at this point.

In accordance with the present invention, 50 a broad collar or band 8 encircles the leg portion of the sock above the calf, and has the inner edge thereof suitably rigidly secured to the leg portion of the sock, said band being of slightly downwardly flared form as shown, and being of a size predetermined by the weight of the person for whom it is made.

Substantially triangular longitudinal or vertical webs 9 of strong flexible material, are fastened in spaced relation on the leg of the sock beneath the band or collar 8, said 60 triangular members or means being secured edgewise against the under surface of the collar 8 and extending downwardly on the leg of the sock with the inner edges thereof secured to the latter.

These radial veins divide the space beneath the collar 8 into a plurality of compartments and the collar 8 is provided with a plurality of openings 10, each of which communicates with one of said compartments adjacent the inner edge of the collar 8. These openings permit a slow passage of water through the collar 8 so as to relieve the latter of undue strains in the use of the device. The veins or webs 9 prevent turning of the collar 8 inside out or flexing of the same toward the knee to an undue extent.

The sock is provided further with semi-cone shaped cups or pockets 11 above the ankles at each side of the strap, said pockets being provided with relatively large lower open ends and having small openings as at 12 at their upper ends to operate similar to the openings 10 for relieving the pockets 11 of undue strain.

In operation, the parts 8, 9 and 11, while drawing the legs toward the body in the water, will lie close to the legs due to the force of the water, and in extending the legs 90 as in swimming and "treading water", will open as shown in the drawings for offering resistance to the passage of the foot and leg thru the water for thereby causing forward travelling movement of the user.

The device is preferably constructed of canvas, duck, or rubber, preferably the latter, and it is essential that the elements be flexible so as to operate as described above and provide for the comfort of the user.

Minor changes may be made without departing from the spirit and scope of the invention as claimed.

What I claim as new is:

1. A swimming and bathing appliance of 105 the character described including a sock having a downwardly flared collar secured to the leg portion thereof, flexible webs secured longitudinally of the leg portion of the sock and having their upper edges secured to the under surface of the collar for preventing turning of the latter upwardly

- to an undue extent, said webs being arranged in uniformly spaced relation in a circular series about the leg of the sock and dividing the space beneath the collar into a plurality of compartments, and relatively small openings being provided thru the collar adjacent the inner edge of the latter, each opening communicating with one of said compartments.
- 10 2. A swimming and bathing appliance of the character described including a sock having a downwardly flared collar secured to the leg portion thereof, flexible webs secured longitudinally of the leg portion of the sock and having their upper edges secured to the under surface of the collar for preventing turning of the latter upwardly to an undue extent, substantially semi-cone shaped pockets provided on the sides of the 15 sock directly above the ankle portions of the latter, said pockets having relatively large open lower ends, and relatively small open-

ings being provided through the upper ends of the pockets.

3. A swimming and bathing appliance of 25 the character described including a sock having a downwardly flared collar secured to the leg portion thereof, flexible webs secured longitudinally of the leg portion of the sock and having their upper edges secured to the under surface of the collar for preventing turning of the latter upwardly to an undue extent, substantially semi-cone shaped pockets provided on the sides of the 30 sock directly above the ankle portions of the latter, said pockets having relatively large open lower ends, relatively small openings being provided through the upper ends of the pockets, and means for preventing accidental rolling of the socks downwardly on 35 the leg of the wearer.

In testimony whereof I affix my signature.

WILLIAM BERGERSON.
